DESIGN FOR A CONTAINER FOR TACKS

Howard E. Holland, Baltimore, Md.

Application September 2, 1936, Serial No. 64,686

Term of patent 3½ years

To all whom it may concern:

Be it known that I, Howard E. Holland, a citizen of the United States of America, residing at Baltimore, county of Baltimore, State of Maryland, have invented a new, original, and ornamental Design for a Container for Tacks, of which the following is a specification, reference being had to the accompanying drawing, forming part thereof:—

The figure is a perspective view of a container

for tacks showing my new design. The figure illustrates two sides of the container for tacks, the sides opposite to the sides shown being substantially the same in appearance.

The top of the container is flat.

I claim:

The ornamental design for a container for tacks, substantially as shown and described.

HOWARD E. HOLLAND.
